[57] CLAIM

The ornamental design for a fuel pressure regulator, as
shown.

DESCRIPTION

FIG. 1 is a front elevational view of a fuel pressure
regular showing my new design; the rear elevational
view being flat, plain and unornamented;

FIG. 2 is a left side elevational view, the right side
elevational view being identical;

FIG. 3 is a top plan view thereof.

The back, side and bottom are plain flat panels.

FIG. - 2

FIG. - 3

FIG. - 1
